UNITED STATES PATENT OFFICE.

JOHN HOLLAND LETZ, OF CROWN POINT, INDIANA, ASSIGNOR TO THE LETZ MANUFACTURING COMPANY, OF CROWN POINT, INDIANA, A CORPORATION OF INDIANA.

GRINDING-BUR.

1,244,516.

Specification of Letters Patent. Patented Oct. 30, 1917.

Application filed May 7, 1917. Serial No. 166,896.

To all whom it may concern:

Be it known that I, JOHN HOLLAND LETZ, a citizen of the United States, and a resident of Crown Point, in the county of Lake 5 and State of Indiana, have invented certain new and useful Improvements in Grinding Burs, of which the following is a full, clear, and exact specification.

My invention is concerned with grinding 10 burs in which the base has a flat annular portion upon which are formed outwardly extending ribs which have their tops ground off flat to present shearing edges to coöperate with similarly formed shearing 15 edges on the opposed bur, and it is designed to produce a bur having a novel design and arrangement of the ribs so that it will grind satisfactorily such diverse articles as corn, oats, beans and short hay.

20 To illustrate my invention, I annex here-to a sheet of drawings, in which the same reference characters are used to designate identical parts in all the figures, of which,—

Figure 1 is a plan view of a portion of a 25 bur embodying my invention;

Fig. 2 is a central section on a reduced scale; and

Fig. 3 is a section on the line 3—3 of Fig. 1.

30 The base A is an annulus, preferably a metal casting having the design in cross section as it appears in Fig. 2, with the inclined, depressed annular portion B surrounding the circular feeding opening, and 35 the pair of customary annular ribs C and D on the back.

The grinding ribs are preferably ar- ranged in similar sections, as shown, with each section occupying one-sixth of the bur.

40 Three extra-long guide ribs E, F and G, substantially parallel to each other and standing at substantially the angle shown to the central radius of the section, serve to guide the materials out to and distribute 45 them somewhat evenly over all portions of the section. Each of these ribs, E, F and G, terminates in a short angularly disposed offset E', F' and G', which preferably ex- tends substantially parallel to the periph- ery of the bur.

50 Associated with each of these elongated ribs are the shorter parallel ribs E^a, E^b, E^c, E^d and E^e; F^a, F^b, F^c, F^d and F^e; and G^a, G^b, G^c, G^d, G^e, which ribs are also provided at their outer ends 55 with the offsets, not lettered, but similar to

the offsets E', F' and G', and their inner ends are usually provided with reversely arranged offsets (also not lettered), the offsets of the outer ends of one series of ribs being arranged in staggered relationship 60 with the offsets of the inner ends of the adjacent series which they closely approach. Two additional series of ribs H^a, H^b, H^c and J^a, J^b, J^c, J^d, J^e and J^f, are provided at 65 the opposite ends of each section, and these series extend in the same general direction and have the same general shape as the other series in the section. All the ribs heretofore mentioned extend to the same height, and have their tops ground off to 70 form shearing edges, as heretofore explained. While I might make all these various ribs unbroken throughout their lengths, as seen in the fragmentary section constituting the right-hand end of Fig. 1, 75 where the ribs E', E^a, E^b, E^c, E^d, E^e and H^a, H^b and H^c are seen, I preferably cut out in each rib two or more recesses K, with said recesses arranged in alinement in the different ribs, so as to furnish a some- 80 what more direct outlet for so much of the material as is finely enough ground before it reaches the periphery.

In addition to the full-height ribs already described, I employ in each section plural 85 series of baffle ribs L, L^a, and L^b; M, M^a, M^b and M^c; N, N^a, N^b and N^c; O, O^a, O^b and O^c; and P, P^a, P^b and P^c, which, as seen in Fig. 3, are slightly lower than the main ribs, and which perform an important function in 90 preventing the material from moving outward too rapidly, and also, paradoxical as it may seem, in preventing the oily materials from clogging in the passages formed by the main ribs. All around the periphery 95 I employ other lower ribs Q, which serve to prevent the escape of the material from the bur before it is completely ground.

What I claim as new, and desire to secure by Letters Patent of the United States, is: 100

1. A grinding plate having on its surface plural series of long shearing ribs with their ground-off tops in the same horizontal plane and arranged to form generally parallel and non-converging passages and all set at a con- siderable angle to radial lines, together with plural series of lower baffle ribs arranged in generally radial lines between the shear- ing ribs. 105

2. A grinding plate having on its surface 110

- plural series of long shearing ribs with their ground-off tops in the same horizontal plane and arranged to form generally parallel and non-converging passages and all set at a considerable angle to radial lines, together with plural series of lower baffle ribs arranged in generally radial lines between the shearing ribs, said shearing ribs being provided with cuts therein arranged substantially parallel to the line of the baffle ribs.
3. A grinding plate having on its surface plural series of longitudinal shearing ribs having their ends offset at an angle of substantially thirty degrees to the line thereof and with their ground-off tops in the same horizontal plane and arranged to form generally parallel and non-converging passages and all set at a considerable angle to radial lines, together with plural series of lower baffle ribs arranged in generally radial lines between the offset ends of the shearing ribs.
4. A grinding plate having on its surface plural series of long shearing ribs with their ground-off tops in the same horizontal plane and arranged to form generally parallel and non-converging passages and all set at a considerable angle to radial lines,

together with plural series of lower baffle ribs arranged in generally radial lines between the shearing ribs, and a line of circumferential baffle ribs, also lower than the shearing ribs.

5. A grinding plate having on its surface plural series of longitudinal shearing ribs having their ends offset at an angle of substantially thirty degrees to the line thereof and with their ground-off tops in the same horizontal plane and arranged to form generally parallel and non-converging passages and all set at a considerable angle to radial lines, and plural series of lower baffle ribs arranged in generally radial lines between the offset ends of the shearing ribs, the ends of one series of longitudinal ribs being arranged in staggered relation to the adjacent ends of the adjacent series of longitudinal ribs.

In witness whereof, I have hereunto set my hand and affixed my seal, this 26 day of April A. D. 1917.
